UNITED STATES PATENT OFFICE

ELLIS WEISKER, OF NEW YORK, N. Y.

PHOTOGRAPHIC APPARATUS

Application filed April 10, 1931. Serial No. 529,018.

The invention relates to photographic apparatus, more particularly as utilized in enlargement work and also of the type employed in so-called "photostatic" work where a reproduction of copy is made directly upon a sensitized paper or other more or less flexible material or film. It has been the general practice in the making of enlargements and photostats to first properly focus the camera by viewing the image on a ground glass or like surface and then replace the ground glass by a box or frame carrying sensitized material disposed in the focal plane of said glass.

It is the object of the present invention to combine the focussing and sensitized material retaining elements, making thereby unnecessary the insertion and removal of a ground glass or like member as well as a swinging or moving of the sensitized material back into place, or the use of a plate holder or the like therefor.

A further object of the invention resides in the provision of a combined focussing screen and retaining member which embodies a plurality of fixed separated focussing elements and intermediate vacuum-providing means which are adapted to retain the sensitized material temporarily to the focussing screen.

A still further object of the invention resides in the provision of means whereby the vacuum holding means may be localized substantially to the particular area corresponding to the size of sensitized material to be held.

A still further object of the invention resides in a novel construction of the surface of the retaining elements and whereby a more efficient grip is attained upon the material held.

In carrying out the invention, a plurality of focussing elements, such as glass panels ground on one face, are fixedly secured in a frame adjacently one another but spaced to afford openings for the introduction of vacuum-providing means. These vacuum-providing means may be fixedly located between the ground glass panels, or they may be arranged to move over the unground surface

of the panels and be adapted for insertion as required into the spaces between panels to afford a vacuum substantially in the focal plane of the ground glass surfaces.

In the former embodiment, as well as in the latter, provision may be made for cutting off the vacuum to a desired suction-affording member.

The active holding surface of a vacuum-providing member may, furthermore, be longitudinally grooved at intervals, the grooves being in communication with the vacuum orifice. This arrangement provides for a better retaining action.

The present invention is a continuation in part of my prior application, Serial No. 224,289, filed October 6, 1927.

In the accompanying drawings which illustrate the invention, Fig. 1 illustrates, in perspective, the front of the novel combined focussing and retaining member and shows also a sheet of sensitized material in position thereon.

Fig. 2 is a fragmentary rear view thereof.

Fig. 3 is a fragmentary transverse section, on an enlarged scale, and taken on the line 3-3, Fig. 2 of the drawings.

Fig. 4 is a fragmentary transverse section and illustrates a modification.

Fig. 5 is a perspective fragmentary view of a portion of the retaining and vacuum-providing member.

Fig. 6 is a rear elevation illustrating a modification in the combined focussing screen and retaining member.

Fig. 7 is a fragmentary transverse section thereof on an enlarged scale taken on the line 7-7, Fig. 6 of the drawings.

Fig. 8 is an enlarged fragmentary horizontal section, partly in elevation, illustrating the manner of inserting the vacuum-providing means in its operative position with respect to the focussing elements.

Referring to the drawings, 10 designates a frame or rectangular structure which may be supported in any suitable manner for use with an enlarging or photostatic camera (not shown). Within the said frame is fixed, either horizontally as indicated in Figs. 1 and 2, or vertically as indicated in Fig. 6, a

5 plurality of adjacently disposed sections or translucent members such as the horizontally disposed ground glass panels 11. These panels, in the usual manner, are designed to receive an image on the ground surface and are adapted to be set relatively to the camera or like apparatus in the plane of sharp focus and in manner well understood in the art.

10 As stated, the said panels are separated from one another to provide intermediate spaces in which are located tubes 12 having suction openings 13 substantially flush with the ground surface of the panels. In the 15 embodiments indicated in Figs. 1 to 4, these tubes are in fixed relationship with respect to the panels 11 and are further in communication with a header or like member 14 adapted for connection, as through the housing 15, with suitable vacuum producing means (not shown). By this expedient, suction is provided in the various tubes 13 over the face of the focussing member comprising a plurality of adjacently disposed panels 11.

20 If it be desired, to localize the holding action to the particular area of the surfaces required for retaining a piece of sensitized material 16, as of comparatively small size relatively to the apparatus, provision may be 25 made for cutting off certain of the tubes 13 which are not required. For example, referring to Fig. 4 of the drawings, the outlet 20 from a header 14 may be provided with a valve 21 operable by turning the head 22 of the stem 23 thereof, which stem is threaded into the outer wall of the header, as indicated. Thus, not only may the suction be 30 regulated to the particular degree but the same may be entirely cut off from those sections of the panels which are not employed for holding of the sensitized material 16.

35 It is not necessary, however, that these vacuum affording means be maintained in fixed relationship to the panels, and in Fig. 6 an arrangement is disclosed whereby a plurality of tubes 25 are movably mounted over the back of the ground glass panels 26 which are provided with intermediate spaces 27. For example, the tubes may be slidably 40 mounted upon a pair of upper and lower rods 28 and are individually connected through hoses 29 and 30 to different sets of sources of vacuum 31 and 32. By grouping the vacuum supplies in this manner, a more uniform 45 vacuum is attainable at the ground glass surface of the panels; and valves 33 and 34 may be provided in the respective hose connections to limit the vacuum to the particular sections of the panels desired for holding. It is to be understood that the tubular members 25 are similarly provided with longitudinally disposed perforations 35 and that the tubes are arranged to be inserted in the spaces 50 27 with their openings 35 brought substan-

tially flush with the ground glass surface of the panels.

This may be accomplished readily by slidably mounting the tubes on rods 36 extending toward the panels from the blocks 37 slidable 55 on the rods 28. In Fig. 8, the full-line position indicates a tube in position for retaining a strip of sensitized material to the panels and the showing in dotted lines indicates its position when retracted to permit of movement over the back of the panels.

The holding surface of the aforesaid tubular retaining members may be constructed to afford a more uniform and satisfactory holding if the same be gouged out or grooved longitudinally to provide a succession of adjacent grooves 40, Fig. 5, with intermediate smooth portions 41 representing the normal outer surface and designed to lie substantially flush with the ground glass surface of the panels. The grooves 40, furthermore, are arranged to be in communication with a perforation 42 from the interior of the tube and will thus distribute the suction along the series of grooves for the particular group, end transverse grooves 43 being also arranged to allow for intercommunication, as well as a transverse groove 44 at the perforation 42. The latter transverse groove, however, does not extend to the final side grooves of a group as it would tend otherwise to reduce thereby the effective vacuum.

I claim:

1. A combined focussing screen and retaining member for sensitized material, comprising a series of fixed, separated translucent sections, and means to apply suction to one surface of the sections through the intervening spaces. 100

2. A combined focussing screen and retaining member for sensitized material, comprising a series of fixed, separated translucent sections, and intermediate vacuum-providing means operating substantially in the focal plane of said sections. 105

3. A combined focussing screen and retaining member for sensitized material, comprising a series of fixed, separated translucent sections, and intermediate movable vacuum-providing means operating substantially in the focal plane of said sections. 110

4. A combined focussing screen and retaining member for sensitized material, comprising a plurality of ground glass panels separated from one another, and vacuum-providing means located in the intermediate spaces. 115

5. A combined focussing screen and retaining member for sensitized material, comprising a series of fixed, separated translucent sections, intermediate vacuum-providing means operating substantially in the focal plane of said sections, and means to control the suction in said vacuum-providing means. 120

6. A combined focussing screen and retain-

ing member for sensitized material, comprising a frame, a plurality of ground glass panels fixedly mounted therein and separated from one another, and vacuum-providing means movable over the back of the frame and adapted to be inserted in the said spaces between panels.

7. A combined focussing screen and retaining member for sensitized material, comprising a frame, a plurality of ground glass panels fixedly mounted therein and separated from one another, and vacuum-providing means movable over the back of the frame and including a tube slidable along the back of the frame and slidable also in a direction at right angles to its sliding motion on the frame, said tube being longitudinally perforated at its forward face and adapted to fit in the spaces between the glass panels with perforations substantially flush with the ground surface thereof.

8. A combined focussing screen and retaining member for sensitized material, comprising a series of fixed, separated translucent sections, and intermediate vacuum-providing means including a tubular member perforated longitudinally and having a succession of surface grooves about a perforation and communicating therewith.

9. A combined focussing screen and retaining member for sensitized material, comprising a series of fixed, separated translucent sections, and intermediate vacuum-providing means including a tubular member perforated longitudinally and having a succession of longitudinal surface grooves about a perforation and communicating therewith, and intermediate flat surfaces.

10. A combined focussing screen and retaining member for sensitized material, comprising a series of fixed, separated translucent sections, and intermediate vacuum-providing means including a tubular member perforated longitudinally and having a succession of longitudinal surface grooves about a perforation and transverse surface grooves communicating with the longitudinal grooves.

In testimony whereof I affix my signature.
ELLIS WEISKER.
